UNITED STATES PATENT OFFICE

JOHN M. MCCLATCHIE, OF NEW YORK, N. Y., ASSIGNOR TO THE BORDEN COMPANY, OF NEW YORK, N. Y., A CORPORATION OF NEW JERSEY

MACHINE FOR WASHING CANS AND THE LIKE

Application filed September 22, 1931. Serial No. 564,349.

The invention relates to an improvement in machines for washing cans and the like, and more particularly to an improvement in handling cans at the discharge end of a machine in which cans are moved step by step through the machine in inverted position, the interior or inner surfaces of the cans are subjected to treatment such as washing, sterilizing and drying operations, and the cans are then uprighted to enable the introduction of covers into the mouths of the cans, the washing of the lower surfaces of the bottoms of the cans, or other operations. The can covers are moved step by step along a path parallel in general to the path of the cans and in order to apply the covers to the cans each can after uprighting onto a receiving platform is moved transversely of the machine to a point beneath the path of the covers. More specifically this invention is an improvement upon that disclosed in my copending application Serial No. 444,963, filed April 17, 1930. In the machine of said copending application the feeding of the cans is effected by means of a can carriage having an upward, forward, downward and rearward movement. The uprighting action is also initiated by the can carriage. After the uprighting and transverse movement of the can has been effected, the can and corresponding cover are advanced simultaneously and the cover falls into the open mouth of the can.

The object of the invention is to produce a can washing machine in which the uprighting and positioning of the cans at the discharge end of the machine are effected with greater certainty than heretofore. In accordance with this object one feature of the invention consists in the provision of novel means for shifting an uprighted can transversely of the machine. This shifting means includes a finger to engage the bottom of the can, a chain carrying said finger and mounted on sprocket wheels so that its upper stretch moves in a transverse slot in the receiving platform, and means operated by downward movement of the can carriage for moving said finger to can-engaging position just before the uprighted can reaches the platform

and by upward movement of the carriage for moving the can to the other side of the machine. Another feature of the invention relates to means to assure the completion of the uprighting of a can. This means includes a member or plate which at the time a can summersaulted is in raised position and is lowered during the rearward movement of the can carriage. The upward movement of the plate takes place during the forward movement of the can carriage.

The preferred form of the invention is illustrated in the accompanying drawings, in which Fig. 1 is a sectional elevation of the discharge end of the machine, the section being taken on the line 1-1 of Fig. 6; Fig. 2 is a fragmentary elevation, partly in section, of the connection through which the movements of the can carriage are utilized to assure the proper positioning of each can after the uprighting thereof; Fig. 3 is a section taken on the line 3-3 of Fig. 2; Fig. 4 is an enlarged section taken on the line 4-4 of Fig. 1; Fig. 5 is an enlarged elevation of the right hand side of the machine at its discharge end, certain parts being omitted in order to show the other parts more clearly; Fig. 6 is a horizontal section through the discharge end of the machine above the stationary bars on which the cans are supported in inverted position during the various cleansing and drying operations; Fig. 7 is a top plan view of the discharge end of the machine, certain parts being shown in section and other parts being omitted to show the underlying structure; Fig. 8 is a sectional elevation on a larger scale of the can adjusting means shown in Fig. 5; and Fig. 9 shows the parts in the positions assumed thereby just as an unwashed can has been placed in the machine, a washed can has been uprighted, and the can-transporting carriage is about to rise.

The improvement of the present invention is illustrated as embodied in a machine comprising a can support consisting of two longitudinally arranged bars 10 on which the cans 11 are supported in inverted position during the various operations of washing, sterilizing and drying. The can sup-

porting bars 10 are provided with legs 12 mounted on cross pieces 13 supported at each end by upright standards 14 forming part of the main or stationary frame of the machine. The bars 10 extend throughout the length of the machine, the right hand ends of the bars, viewing Fig. 9, constituting the intake end of the machine and the left hand ends of the bars being at the point at which the cans are uprighted onto the discharging platform indicated at 15. The spray nozzles for directing the washing, sterilizing and drying fluids into the cans extend upwardly from the can supporting bars 10 and are fixed in position between these bars by brackets 16.

The cans 11 are advanced through the machine from the intake end to the discharge end and are successively lowered over the nozzles for effecting the treating operations by means of a transporting carriage or frame shown most clearly in Fig. 9. The can transporting carriage comprises two longitudinally extending oppositely-faced angle bars 17 which are spaced far enough apart to support the flanged mouths of large milk cans of the usual types. The bars 17 are supported on the inner edges of the transversely arranged pieces 18 which are secured to the lower ends of the inner uprights 19 and the outer uprights 20. The uprights 19 and 20 are held apart in spaced relation by three longitudinally extending angle beams 21, the upper channel iron 22 and the cross piece 23, so that the carriage is sufficiently rigid to perform the four-step cycle in transporting the advancing cans through the machine without vibration. The carriage is provided with an outer guard plate 24 secured to the inner side of the uprights 20 and with an inner guard plate 25 secured to the inner sides of the uprights 19. The angle irons 26, secured to the inner sides of the plates 24 and 25 with the apexes of their angles oppositely disposed, extend throughout the carriage so as to assist in preventing chafing of the plates 24 and 25 by the cans during the movement of the carriage with respect to the cans.

The means for imparting the four-step cycle of movements to the carriage to advance the cans through the machine and to place them over the nozzles comprises two rectangularly-shaped gear frames 27 and 28, secured to the under sides of the inner set of angle beams 17. Each frame 27 and 28 is provided with a four sided internal gear the teeth of which constitute a rack to be engaged by a pinion 29. The pinions 29, are mounted on the inner ends of transversely arranged shafts 30 journalled at their ends in frames 31 supported at their inner ends on angle irons 32 secured to the cross pieces 13 and at their outer ends on the angle irons 33 secured to uprights 14. On the outer

ends of the shafts 30 are mounted the beveled gears 34 in mesh with the pinions 35, one of which is mounted on one end and the other of which is mounted on the other end of the longitudinally arranged shaft 36 journalled at its ends in bearings 37 extending outwardly from the frames 31. The shaft 36 may be driven from any convenient source of power and for this purpose is provided with sprocket wheel 38 and chain 39.

The shaft 36 rotates in a counter-clockwise direction, viewing Fig. 1. From this it will be readily understood that, while the rotating pinions 29 are in mesh with the teeth of the upper gear sections of the frames 27 and 28, the can carriage is traveling rearwardly or toward the intake end of the machine; that, while the pinions are in engagement with the upright gear sections toward the intake end, the can carriage is rising or traveling upwardly; that, while the pinions are in engagement with the lower gear sections, the can carriage is advancing toward the discharge end of the machine; and that, while the pinions are in engagement with the gear sections toward the discharge end, the can carriage is descending or traveling downwardly. The travel of the can carriage is substantially continuous, even at the point where it changes its direction of travel. However, the end of the rearward movement or travel toward the intake end of the machine may be regarded as the point of beginning of the four-step cycle of movements of the carriage in transporting the cans through the machine. The carriage travels from the end of its downward stroke to the beginning of its upward stroke freed from the cans. During this movement of the can carriage the cans remain stationary on the can supporting bars 10. The angle beams 17 of the can carriage deposit the cans on the supporting bars 10 just before the completion of the downward stroke of the carriage, and the angle bars 17 re-engage the cans just after the beginning of the upward travel of the carriage.

The can carriage is sustained during its upward and downward travel and while the pinions 29 are in engagement with the lower gear sections by means of the rolls 40 concentrically alined with the shafts 30, respectively, and traveling in the grooves 41 formed in the rear sides of the gear frames 27 and 28 as best shown in Figs. 5, 7 and 9. The rolls 40 are mounted in the journals 42 resting on and secured to the longitudinally extending angle irons 43 supported at their ends on cross pieces 13. The gear frames 27 and 28 are guided in their movement by the angle irons 32 and 43, and the upper part of the uprights of the can carriage are guided by the longitudinal angle irons 44 supported on the cross pieces 45 resting on the

top ends of the uprights 14 of the stationary frame of the machine.

The nozzles (of which only the last three are shown) for directing the washing, sterilizing and drying fluids into the can may be regarded as stations at which each can pauses for treatment. As indicated by the cans in Fig. 9, there are nine stations and these correspond in position to the positions 10 of the first nine cans counting from the right. The first two stations include false nozzles and are provided partly to afford the operator opportunity to place an inverted can in the machine, as at the right hand station, 15 and partly to permit the milk or other substance remaining in the can to run out before the can is subjected to the preliminary cold water rinse. At the other stations the interior of the can is subjected in succession 20 to a cold water rinse, a hot water rinse, the direction of a washing solution into the can, the removal of the washing solution from the interior of the can by a hot water rinse, a steam bath, and a stream of air directed 25 into the can to dry it. As indicated on Fig. 6, the air is supplied at the last station 46 through a branch duct 47 connected with a main air duct 48 leading from a suitable source of air such as a conveniently located 30 blower.

The carriage passes through its four-step cycle of movements to advance the cans along the can supports and place the cans at the treating stations successively in the following manner:—Assuming that the position of 35 the carriage at the end of its movement toward the intake end of the machine is the beginning of its four-step cycle of movements, and that an operator has placed a can in inverted position over the false nozzle at the first station, as indicated by the right hand can in Fig. 9, the first movement of the carriage is upward, bringing the angle beams or bars 17 into engagement with the 40 flanged mouth of such can, and lifting the can from the bars 10. The next movement of the carriage is toward the discharge end of the machine, and at the end of this movement the can is positioned above the false nozzle at the second station. The next movement of the carriage is downward, lowering the can over the false nozzle at the second station until the flanged mouth of the can rests on the can supports 10, and then freeing 45 the bars 17 from the can just before the completion of the downward movement. The fourth or final step of the cycle of movements of the carriage is the return movement toward the intake end of the machine to the 50 position shown in Fig. 9. During the next four-step cycle of movements of the carriage, the can which had been placed over the second station is advanced to the third station where it receives the first or preliminary 55 treatment. During succeeding, continued

four-step cycles of movements of the carriage the can in question is shifted from one station to another until after treatment by the air nozzle at the last station 46 it is raised from the air nozzle at that station. 70 On the next movement of the carriage toward the discharge end of the machine the can is moved to a position over a summersaulting device indicated generally at 49, so that on the succeeding downward movement the can will be turned over into upright position on the platform 15, as shown in Fig. 5.

During the normal, continuous operation of the machine nine cans are advanced simultaneously, one from each of the nine stations. 75 In order to keep nine cans constantly in the machine, the operator places an inverted can at the first station (indicated by the right hand can Fig. 9) when the carriage has removed the can therefrom and carried it to the second station. While the cans remain at the first two stations, any milk residue in them drains into a pan 50 supported on the first two cross pieces 13. The pan 50 discharges into a sewer or other convenient 80 drain. At the remaining stations, the interiors or inner surfaces of the cans are subjected to the series of treatments whereby 85 they are thoroughly cleansed, sterilized and dried.

While the cans are passing through the machine and undergoing the washing, sterilizing and drying operations, the covers to the cans are also passing through the machine and are subjected to a similar washing, sterilizing and drying treatment. The runway along which the covers are advanced occupies the space above the fluid controlling means at the right hand side of the machine, looking in the direction of movement of the cans. The covers are supported topside up in oblique positions on two rails 63 and 64 fixed on a series of frames or brackets 65 secured to the cross pieces 45. Each can cover consists of a flanged top portion 66 and a cylindrical or tubular neck portion 67 which fits in the mouth of the can. The covers are adapted to be slid along the rails 63 and 64 and since these are arranged on an inclined plane and the rail 64 is lowermost the cylindrical part of the cover will bear against the rail 64. The rails 63 and 64 extend from a point opposite the first station at the inlet end of the machine to a point 90 over the discharge platform 15, as shown in Fig. 9.

The means for advancing the covers step by step along the rails 63 and 64 comprises a series of fingers 68 secured to a longitudinally extending bar 69 connected at each end by a boss 70 with a shaft 71 journaled in bearings 72 supported from the cross pieces or braces 73 in the upper part of the frames 65, and arranged to have reciprocatory and oscillatory movements imparted to it from the 100 105 110 115 120 125 130

can carriage. The shaft 71 is positively oscillated in the direction to lift the fingers 68 above the plane passing through the top surfaces of the can covers and is yieldingly oscillated in the opposite direction to place the fingers 68 in cover-engaging position, and is also positively advanced and retracted. For this purpose the shaft 71 is provided with an arm 74 the free end of which projects through slotted plate 75 secured to the rear-most upright 19 of the can carriage, a contraction spring 76, the lower end of which is attached to the arm 74 and the upper end of which is attached to the channel beam 22 normally holds the free end of the arm against the top of the slot in the plate 75, as shown in Fig. 9. On the down stroke of the can carriage, plate 75 depresses the free end of arm 74 and so oscillates the shaft 71 to lift the fingers 68 above the can covers. As the can carriage rises the spring 76 holds the free end of the arm 74 against the upper end of the slot in plate 75 and thereby causes the shaft 71 to place the fingers in cover-engaging position. If during the movement of the fingers 68 into cover-engaging positions one of the fingers should encounter a misplaced cover the spring 76 will yield while the can carriage and plate 75 complete their upward travel, and thus no injury will occur to any of the parts of the machine. While the fingers 68 are held above the tops of the can covers by the engagement of the part 75 with the arm 74 the can carriage is moving toward the intake end of the machine and so the shaft 71 and fingers 68 move in that direction with it, and while the fingers 68 are in cover-engaging position the can carriage is moving toward the discharge end of the machine and consequently the fingers 68 advance the covers one step.

When the operator places the can in inverted position at the first station he places the cover on a hopper-like chute indicated generally at 77. The chute is obliquely arranged and is provided with the obliquely arranged bottom, the bottom and other parts being suitably supported on the stationary frame of the machine. When the can is placed in inverted position at the first station the cover for the can is placed top side up in the chute, the lower edge of the cylindrical neck of the cover resting on the bottom of the chute. The cover then slides down the chute until the cylindrical neck portion thereof rests against the outer end of the lower rail 64 of the cover runway.

As a matter of practice, the operator places the cover in the chute 77 before he places the inverted can at the first station. The cover remains in the chute until its corresponding can has been placed at the first station and the carriage has risen to lift the can. This method of operating is employed to prevent a cover from advancing through the machine

unless accompanied by its can. Placing of the can in inverted position at the first station renders effective a pin (not shown) connected with the can carriage so that upon upward movement of the can carriage said pin will engage a cam arm 78 extending upwardly from a hub 79 pivotally mounted on the stationary frame. As the can carriage rises the hub 79 is turned and an arm 80 (also fixed on hub 79) is swung into engagement with the cover in the chute 77 and moves it forward to the position corresponding with the second station in Fig. 9. The distance from the chute 77 to the point to which the cover is moved by the arm 80 equals one longitudinal step of the carriage. This action takes place while the can carriage is rising and before it completes its full upward stroke. As the can carriage completes its upward stroke a finger 81 carried by the first upright 19 of the carriage is placed behind the cover so that on the next forward step of the carriage the cover at the position just referred to is moved forward to the position corresponding with the third station, which position is within range of the first cover-engaging finger 68.

The covers are subjected to the same kind of cleansing treatment as that to which the inner surfaces of the cans are subjected, namely, washing, steaming and drying. The station at which these operations on the cover are effected correspond respectively to the stations at which the cans are treated except that the cover cleaning stations are one step in advance of the can treating stations in order to secure the automatic placing of the cover in its can under the action of gravity. As illustrated in Figs. 1 and 6 the last can treating station 46 is provided with an air nozzle connected by a suitable duct 47 connected with the main air duct 48.

When the dried can has been lifted from over the nozzle at the last station and advanced through the next forward step of the can carriage it is positioned over the summersaulting device 49, as indicated above, so that on the next downward movement of the carriage the can is turned in upright position on the platform 15. The summersaulting device 49 comprises a platform consisting of a horizontal section 82 and an oblique section 83 provided with an upturned lip 84. The horizontal section or part 82 of the summersaulting device 49 is supported by two uprights 120 rising from the forward end of the can-supporting bars 10. By referring to Fig. 9 it will be evident that the center line of each can lowered on the horizontal section 82 is slightly to the left of the point of junction 125 between the horizontal section and the slanting section of the summersaulting device. Consequently when the carriage on its downward stroke leaves the can on the platform 82, 83, the can immediately tilts, and the 130

mouth of the can slides down the incline constituting the oblique section 83. The momentum of the can carries it forward and the cylindrical portion of the can strikes 5 against a transversely arranged flexible bar or spring 87 supported by standards 88 rising from a channel iron 89 transversely arranged across the discharge end of the machine and determining the rear edge of the platform 10 15. The momentum of the falling can as it strikes the spring 87 is sufficient to cause the can to turn right side up onto the platform 15 as shown in Figs. 5 and 9. In order that the mouth of the can may not slide backwardly along the horizontal section 82 of the platform as the cylindrical part of the can strikes the spring 87, there is provided a deflecting finger or deflector 90 extending upwardly from the center of the forward 20 edge of the horizontal platform section 82. The deflector 90 is seldom brought into operation because the great majority of the cans will summersault over the spring 87 without moving axially. Occasionally, however, a 25 can will tend to move inwardly and in that case the deflector 90 prevents the sliding of the mouth of the can along the platform section 82 and the can will be properly uprighted on the platform 15. As the can is 30 summersaulted it is guided between two guards 91 extending from the rear or discharge end of the can carriage.

The platform 15 of which the channel iron 89 determines the rear edge extends 35 transversely across the discharge end of the machine and is supported by the longitudinal channel irons 92 extending from the next to last pair of uprights 14 to the final, short pair of uprights 14. At its forward edge the 40 platform is supported by a channel iron 93 extending transversely of the two final uprights 14. The cans are discharged onto platform 15 at a point in alignment with the bars 10. At its forward edge and opposite 45 the spring the platform is provided with the upright guard plate 94 to prevent the uprighting can from toppling off the end of the machine. At the left hand edge of the platform 15 there is a guard plate 95 which 50 extends from the next to the last upright to the last upright at the left hand side of the machine.

The mechanism thus far described is substantially the same as corresponding mechanism disclosed in said copending application and has been disclosed principally to make clear the operation of the can handling mechanism at the discharge end of the machine.

60 The uprighted can is moved transversely across the discharge end of the machine on the platform 15 into position to receive a spray of water against its bottom previous to receiving its cover and to its discharge from the machine, which actions take place simultaneously. The movement of the uprighted can transversely of the discharge end of the machine is effected by means of a finger 95a projecting upwardly above a transversely extending slot 96 and reciprocated along said slot by means of an endless chain 97 to which it is attached. The endless chain 97 is mounted on an idler sprocket wheel 98 rotatively supported by brackets 99 projecting from the web of the left hand channel 92 and a driving sprocket wheel 100 fixed on a driving shaft 101 journaled in brackets 102 projecting downwardly from the bottom of the platform 15. The sprocket wheels 98 and 100 are so arranged that the upper reach or stretch of the chain 97 is positioned in the slot 96, and said upper stretch is supported by a plate 103 at the lower side of the platform 15. The shaft 101 is driven from the oscillating shaft 56 which is oscillated by a connection with the cam frames including a rod-like arm 58 projecting from the shaft and having its outer end slidably received in a sleeve 59 provided with a head 60 slidably mounted on a rod 61 carried by the lower end of the downward extension 62 of the gear frame 27. The arrangement is such that when the can carriage descends the shaft 56 is turned in a clockwise direction, looking from the discharge end of the machine, and when the can carriage rises the shaft 56 is turned in a counter-clockwise direction. When the can carriage is moving longitudinally either toward the discharge end of the machine or toward the intake end thereof the rod 61 slides in the head 60 and the shaft 56 remains stationary.

Also fixed on the driving shaft 101 is a sprocket wheel 104 which is connected by a sprocket chain 105 with a sprocket wheel 106. Coaxial with the sprocket wheel 106 and secured thereto is a sprocket wheel 107. The double sprocket wheel thus formed is rotatably mounted on a bracket 108 attached to two cross members 109 and 110 connecting the uprights 14 at the discharge end of the machine. The sprocket wheel 107 is driven by means of a sprocket chain 108a of which the ends are secured to a member 109a fixed on the oscillating shaft 56. As here shown, the member 109a has two parallel sides and arcuate ends on which the sprocket chain 108a wraps and unwraps, the ends of the chain passing around said curved ends and being secured to the member 109a at its farther side by suitable means, such as screws 110a. It will be evident that oscillation of the shaft 56 will cause reciprocation of the finger 95a and that the connections can be so designed as to produce the desired movement of this finger. In said copending application the cans are moved across the platform 15 by a swinging arm of which the point of contact with the can varies vertically during the shifting movement. With

the present arrangement there is no such variation.

Bearing in mind that the shaft 56 is turned in a clockwise direction, viewing Fig. 1, as the can carriage descends, it will be seen that the finger 95a is returned to normal position as indicated in dotted lines, when the can carriage descends, and that, on the upward movement of the can carriage the finger 95a is moved to push the can across the discharge end of the machine and to a position under the cover runway, as indicated in full lines. Although the finger 95a is moved into normal position as the can carriage is descending and the dried can is being summersaulted onto the platform 15, the parts are so timed in their movements that the can-engaging finger reaches the position shown in dotted lines in Fig. 1 just before the bottom of the can comes down onto the platform. The finger 95a then remains stationary while the can carriage travels toward the intake end of the machine and on the next upward movement of the carriage the finger makes its can-shifting movement. As the can approaches the right hand side of the platform 15 the rear side of the can encounters a cam plate 111 fixed on the channel iron 89 and is deflected forwardly by it.

As the can reaches the right hand side of the platform, it moves onto the free end of a plate-like lever 112 pivoted at 113 in the extensions 114 of the platform 15. The under surface of the plate 112 is provided with an adjustable valve actuating member 115 which rests on the upper end of the valve stem 116 of the valve 117 which controls the passage of hot water from the pipe 118 to the nozzle 119 for directing the spray against the bottom of the can. While the can remains in contact with the plate 112 it presses the plate down and thereby opens the valve 117. The can continues in engagement with the plate 112 while the can carriage is moving forward, during which time the bottom of the can is thoroughly washed by the spray from the nozzle 119. In order that no damage may be done either to the can or to the finger 95a as the can reaches the end of its travel across the platform a yieldingly mounted guard rail 120 is provided at the right hand side of the platform 15. The rear end of the rail 120 is secured to a pivot pin 121 journalled in a bracket 122 supported from the channel iron 89. A spring 123 encircling the upper end of the pin yieldingly holds an offset part 124 of the free end of the rail against the end of the platform 15. The bottom-washing means just described forms no part of the present invention but is so closely associated therewith that it appears desirable to describe its operation as controlled by the movement of the cans at the discharge end of the machine.

The can reaches its position at the right

hand side of the platform 15 just about as the carriage completes its upward travel. As the carriage begins its next forward step an upright finger 125 carried by a bracket 126 extending forwardly from the inner side of the front end of the can carriage engages the rear side of the can which is now pausing over the nozzle 119 and pushes it forward off the platform and onto a conveyor of usual form the intake end of which is indicated at 127. The finger travels in a slot 128 in the platform 15. This means for delivering cans to the conveyor, which is the same as that disclosed in said copending application, is utilized to operate a device for adjusting the position of each can summersaulted into position on the platform. This device includes a member or plate 129 arranged vertically opposite the summersaulting device and means whereby the plate is placed in raised position at the time of the summersaulting operation and prevents excessive movement of the open end of the can at the end of this operation. The plate remains in raised position during the downward movement of the can carriage but moves downwardly during the return movement of the carriage toward the can-receiving end of the machine and, if the lower end of the summersaulted can is too far in advance of the rest of the can, engages the body of the can, for example, at the lower edge and straightens the can as well as moves it into proper position for engagement by the finger 95a on the transversely extending sprocket chain. The plate 129 is mounted on a sprocket chain 130 carried by sprocket wheels 131 and 132 of which the lower one 131, Fig. 8, is mounted on a shaft 133 journalled in a bracket 134 projecting from a channel 135 connecting the uprights 14 at the discharge end of the machine, and the upper one 132 is mounted on a shaft 136 vertically above the shaft 133 and is journalled in opposite sides of a casing 137 projecting upwardly from the platform 15 and substantially enclosing the sprocket chain above the platform. As shown in Fig. 8, the casing 137 is formed as part of the plate 94 which has a slot 138 in which runs one stretch of the chain so that the plate 129 extends across the slot. The chain 130 is not endless, the end extending upwardly from the lower sprocket wheel 131 to the plate 129 terminating in a link 139 which is permanently attached to the plate 129 at its rear, and the other end of the chain terminating in a screw-threaded rod 140 which passes through an eye 141 projecting from the rear of the plate. By means of one or more nuts 142 on the rod 140 the tension of the chain 130 can be regulated as desired. The upper shaft 136 is an idle shaft but the lower shaft 133 is utilized for actuating the chain and for this purpose is provided with another sprocket wheel 143 which is connected by a

horizontally arranged sprocket chain 144 with an idler sprocket 145 rotatably supported on the frame of the machine at a point between the uprights 14 of the next to last 5 pair at the discharge end of the machine. In its upper stretch, the sprocket chain 144 is provided with a link 146 from the side of which projects an eye 147 slidably enclosing a vertical rod 148 mounted at its upper and 10 lower ends in lateral projections of a bracket 149 secured at its upper end to the bracket. With this arrangement upward and downward movement of the can-carrying carriage will have no effect on the position of the 15 plate 129, but movement of the carriage to advance the cans will raise the plate and movement of the carriage in the opposite direction will lower the plate.

As described in said copending application, each can is advanced step by step from the intake end of the machine to the position over the summersaulting and during this movement of the can the cover therefor is advanced step by step to a position one interval farther along than the can. The downward movement of the can carriage will cause summersaulting of the can but will not affect the position of its cover. During this movement of the carriage the can-shifting 30 finger 95a of the present invention will be shifted to the left of the platform just before the uprighted can is deposited on the platform. In the present machine proper up-righting of the can is assured by the member or plate 129 and the operating means therefor. The forward movement of the can carriage raises the plate to its uppermost position in which it remains during the summersaulting action and thus serves to prevent excessive movement of the upper end of 40 the can. During the rearward movement of the carriage the can shifting finger remains in its extreme left hand position but the adjusting plate moves downwardly and, if the lower end of the uprighted can has been advanced too far, moves it back into the proper position for engagement by the can-shifting finger 95a when the latter is moved to the right as a result of the upward movement 45 of the can carriage. By this movement to the right the can is positioned on the plate 112 and depresses the plate to effect washing of the bottom of the can. During this upward stroke of the can carriage, the final cover engaging finger 68 is placed behind the cover in the final position. Then on the next or final movement of the carriage (so far as the can in question is concerned) the finger 125 pushes the can off the platform 55 onto the conveyor 127 and simultaneously therewith the final finger 68 pushes the cover off the rails 63 and 64 so that the cover falls into the open mouth of the can. This completes the automatic treatment of the can and its cover.

Having thus described the invention, what I claim as new is:—

1. In a machine of the character described, the combination with a trackway along which a can may be conveyed in inverted position, a can feeding carriage having an upward, forward, downward and rearward movement for advancing a can step by step along the trackway, a summersaulting device beyond the end of the trackway effective on the downward stroke of the carriage to upright the can and a platform onto which the can is uprighted; of can-adjusting means including a member vertically movable at the farther side of the position to be assumed by the uprighted cans and means operated by the carriage to lift said member during the forward movement of the carriage and to lower it during the rearward movement of the carriage to complete the up-righting of a can when the up-righting is not completed by the summersaulting device.

2. In a machine of the character described, the combination with a trackway along which a can may be conveyed in inverted position, a can feeding carriage having an upward, forward, downward and rearward movement for advancing a can step by step along the trackway, a summersaulting device beyond the end of the trackway effective on the downward stroke of the carriage to upright the can and a platform onto which the can is uprighted; of can-adjusting means including a member vertically movable at the farther side of the position to be assumed by the uprighted can and means operated by the carriage to lift said member during the forward movement of the carriage and to lower it during the rearward movement of the carriage to complete the up-righting of a can when the up-righting is not completed by the summersaulting device, said means being operated by the carriage including a forwardly and rearwardly movable member having a vertically slideable connection with the carriage whereby this movable member is moved horizontally with said carriage and is stationary during the upward and downward movements of the carriage.

3. In a machine of the character described, the combination with a trackway along which a can may be conveyed in inverted position, a can feeding carriage having an upward, forward, downward and rearward movement for advancing a can step by step along the trackway, a summersaulting device beyond the end of the trackway effective on the downward stroke of the carriage to upright the can and a platform receiving the uprighted can and having a transverse slot; of means for moving the uprighted can along said slot including a horizontally-reciprocable finger mounted to travel along said slot and means operated by said carriage for moving said finger during the downward movement of the

carriage to a position to engage the uprighted can and during the upward movement of the carriage to move the uprighted can along said slot.

- 5 4. In a machine of the character described, the combination with a trackway along which a can may be conveyed in inverted position, means for advancing a can step by step along said trackway including a carriage having 10 an upward, forward, downward and rearward movement, a cover runway at one side of the path of the cans, means controlled by the carriage for advancing a cover along the runway in timed relation with the advance 15 of the can but one step in advance thereof, a summersaulting device beyond the end of the trackway effective on the downward stroke of the carriage to upright the can and a platform receiving the uprighted can and having a transverse slot extending across the position where the can is received and toward a position beneath the cover runway; of means for moving the uprighted can to the position beneath the cover runway including a sprocket 20 chain, sprocket wheels carrying said sprocket chain so that its upper stretch travels in said slot, a finger projecting from said chain to engage the uprighted can, and means operated by said carriage for actuating said 25 chain and thereby moving said finger to advance an uprighted can to the position beneath the cover runway during the upward movement of the carriage and to move said finger in the opposite direction during the 30 downward movement of the carriage.

- 5 5. In a machine of the character described, the combination with a trackway along which a can may be conveyed in inverted position, means for advancing a can step by step along 40 said trackway including a carriage having an upward, forward, downward and rearward movement, a cover runway at one side of the path of the cans, means controlled by the carriage for advancing a cover along the 45 runway in timed relation with the advance of the can but one step in advance thereof, a summersaulting device beyond the end of the trackway effective on the downward stroke of the carriage to upright the can and a platform receiving the uprighted can and having a transverse slot extending across the position where the can is received and toward a position beneath the cover runway; of can-adjusting means including a number vertically moving 50 at the farther side of the position to be assumed by the uprighted can, means operated by the carriage to lift said member during the forward movement of the carriage and to lower it during the rearward movement 55 of the carriage to complete the uprighting of a can when the uprighting is not completed by the summersaulting device, a finger mounted for rectilinear movement along said slot, and carriage-operated means for moving the finger to advance an uprighted can 60

to the position under the cover runway during the upward movement of the carriage and in the opposite direction during the downward movement of the carriage.

6. In a machine of the character described, the combination with a trackway along which a can may be conveyed in inverted position, means for advancing a can step by step along said trackway including a carriage having an upward, forward, downward and rearward movement, a cover runway at one side of the path of the cans, means controlled by the carriage for advancing a cover along the runway in timed relation with the advance of the can but one step in advance thereof, a summersaulting device beyond the end of the trackway effective on the downward stroke of the carriage to upright the can, a platform receiving the uprighted can and having a transverse slot extending across the position where the can is received and toward a position beneath the cover runway, and a shaft extending longitudinally of the machine, means operated by the carriage for turning the shaft in one direction during the downward movement of the carriage and in the opposite direction during the upward movement of the carriage; of a sprocket chain with its upper stretch extending along said slot, a can-engaging finger projecting from said chain above said slot, and means for actuating said chain to move said finger to advance an uprighted can to a position beneath the cover runway during the upward movement of the carriage and in the opposite direction during the downward movement of the carriage including a driving shaft carrying one of said sprocket wheels, another sprocket wheel on said driving shaft and means for operating the last mentioned sprocket wheel including a sprocket chain connected at its opposite ends with the first mentioned shaft.
